UNITED STATES PATENT OFFICE.

WILLIAM M. BRADSHAW, OF WILKINSBURG, PENNSYLVANIA, ASSIGNOR TO
WESTINGHOUSE ELECTRIC & MANUFACTURING COMPANY, A CORPORA-
TION OF PENNSYLVANIA.

WINDING FOR ELECTROMAGNETS.

No. 853,340.

Specification of Letters Patent.

Patented May 14, 1907.

Application filed April 28, 1906. Serial No. 314,210.

To all whom it may concern.

Be it known that I, WILLIAM M. BRADSHAW, a citizen of the United States, and a resident of Wilkinsburg, in the county of Allegheny and State of Pennsylvania, have invented a new and useful Improvement in Windings for Electromagnets, of which the following is a specification.

My invention relates to windings for electromagnets, and it has for its object to provide a winding of large current-carrying capacity for U-shaped magnet cores which shall occupy a small amount of space and which shall be easy and inexpensive to manufacture.

In the manufacture of electrical instruments and other translating devices it is quite customary to adapt them to different ranges of current capacities by adjusting the numbers of convolutions and the dimensions of the conductors in the windings thereof in accordance with the desired conditions of operation. Thus, magnetizable cores and other parts having substantially identical dimensions may be employed in instruments that differ widely in current capacity. The winding constituting the present invention permits of the adaptation of meters and other devices to higher current-carrying capacities than has heretofore been possible without enlarging the magnetizable cores.

Figure 1 of the accompanying drawing is a view in side elevation of a magnet core having a winding constructed in accordance with my invention, and Fig. 2 is a bottom plan view of the core and winding shown in Fig. 1.

Both legs of an U-shaped magnetizable laminated core 1 are surrounded by a substantially rectangular loop of strap conductor, to one end of which a split terminal piece 3 is rigidly secured. The terminal piece is provided with flanges 4 and 5 along the edges of the split in one of which screws 6 are threaded and by means of which the terminal piece may be clamped about an external circuit terminal (not shown). The magnetizable core 1 is located close to one of the longer sides of the rectangular loop 2 to which is secured, by means of tap screws 8, one end of the body portion of a T-shaped bar or piece 7 that is located between the legs of the U-shaped core. The head of the

T-shaped piece 7 is located in the space between the magnetizable core and the side of the rectangular loop opposite that to which the extremity of the body of the T-shaped piece is secured, and it is extended upwardly out of the plane of the rectangular loop and beyond the end thereof opposite that to which the terminal piece 3 is secured. The extremity of the extension of the T-shaped piece 7 is also provided with a split tubular terminal piece 9 having flanges 10 along the edges of the split, one of which is threaded for the reception of clamping screws 11.

To explain the operation of the invention, it may be supposed that current is supplied to the winding through terminal piece 3, from whence it passes through the sides of the rectangular loop in opposite directions around the legs of the magnetizable core and then through the T-shaped piece 7 to the terminal piece 9. It will be understood from the directions in which the currents traverse the winding that fluxes are induced in opposite directions in the legs of the magnetizable core, and consequently one leg will be the north pole of the magnet and the other the south pole.

Obviously, the structural details of the parts may be considerably varied from what has been specifically shown and described without altering the mode of operation of the invention or departing materially from its spirit and I desire that all such modifications shall be included within its scope.

I claim as my invention:

1. A winding for electro-magnets comprising a loop and a bar that extends from one side of the loop partially across the area included thereby.

2. A winding for electro-magnets comprising a loop, a bar that extends from one side of the loop partially across the area included thereby, and terminal pieces that are attached respectively to the loop and to the free end of the bar.

3. A winding for electro-magnets comprising a loop, and a bar that extends from one side of the loop partially across the area included thereby and thence outwardly from the plane of the loop.

4. A winding for electro-magnets comprising a loop, a bar that extends from one side of the loop partially across the area in-

cluded thereby and thence outwardly from the plane of the loop, and terminal pieces for the loop and the free end of the bar.

5. A winding for electro-magnets comprising a loop and a **T**-shaped piece one extremity of the body of which is joined to one side of the loop.

6. A winding for electro-magnets comprising a loop, a **T**-shaped piece one extremity of the body of which is joined to one side of the loop, and terminal pieces for the loop and the head of the **T**-shaped piece.

7. A winding for electro-magnets comprising a loop, a **T**-shaped piece one extremity of the body of which is joined to one side of the loop and the head of which is extended outwardly from the plane of and beyond the limit of the loop, and terminal pieces for the loop and the extension of the cross bar of the **T**-shaped piece.

8. The combination with an **U**-shaped magnetizable core, of a winding therefor comprising a loop that surrounds both legs thereof and a bar that extends from one side of the loop partially across the area included thereby and between the legs of the core.

9. The combination with an **U**-shaped magnetizable core, of a winding therefor comprising a loop that surrounds both legs thereof, a bar that extends from one side of the loop partially across the area included thereby and between the legs of the core, and terminal pieces for the loop and the free end of the said bar.

10. The combination with an **U**-shaped magnetizable core, of a winding therefor comprising a loop that surrounds both legs thereof, and a **T**-shaped piece the body of which is joined to one side of the loop and is located between the legs of the core and the head of which occupies a space between the core and the other side of the loop.

11. The combination with an **U**-shaped

magnetizable core, of a winding therefor comprising a loop that surrounds both legs thereof, and a **T**-shaped piece the body of which is joined to one side of the loop and the head of which occupies the space between the core and the other side of the loop, and an extension of the head of the **T**-shaped piece that extends outwardly from the plane of and beyond the limits of the loop. 45

12. The combination with an **U**-shaped magnetizable core, of a winding therefor comprising a loop that surrounds both legs thereof, and a **T**-shaped piece the body of which is joined to one side of the loop and is located between the legs of the core and the head of which occupies the space between the core and the other side of the loop, an extension of the head of the **T**-shaped piece that extends outwardly from the plane of and beyond the limits of the loop, and terminal pieces for the loop and the extension of the **T**-shaped piece. 55

13. An electro-magnet coil comprising a loop and a detachable bar one end of which is attached to one side of the loop and the other end of which is adjacent to the opposite side of the loop. 60

14. An electro-magnet coil comprising a loop having a terminal clamp, and a bar that extends from one side of the loop nearly to its opposite side and is provided with a terminal clamp. 65

15. An electro-magnet coil comprising a loop having a terminal connector at one end and a bar that extends from one side nearly to the opposite side and the free end of which is provided with a terminal connector. 70

In testimony whereof, I have hereunto subscribed my name this 23rd day of April, 1906.

WILLIAM M. BRADSHAW
